UNITED STATES PATENT OFFICE.

J. D. CUSTER, OF NORRISTOWN, PENNSYLVANIA.

IMPROVED LAMP-BURNER.

Specification forming part of Letters Patent No. 34,742, dated March 25, 1862.

To all whom it may concern:

Be it known that I, J. D. CUSTER, of Norristown, in the county of Montgomery and State of Pennsylvania, have invented a new and Improved Lamp-Burner; and I do hereby declare that the following is a full and exact description thereof, reference being had to the accompanying drawings, and to the letters of reference marked thereon.

The nature of my invention consists in providing lamps with wide thin wicks and burners which will produce a wide thin low flame, so as to produce the proper quantity of light without putting the wick up so high as to smoke.

The same letters refer to like parts in each figure.

Figure 1 is a perspective view of my lamp. Fig. 2 is a side view of the regulating-cap, and Fig. 3 is a top view of it.

To enable others to make and use my invention, I will proceed to describe its construction and operation.

The letter A, Fig. 1, is the body of the lamp. This I make as they are usually made.

B is the burner. I construct it of brass or any suitable material. It is made to suit old lamps, and has a male screw on the lower end of it, below B, which screws into the female screw on the lamp; but the top of it I make from two to six inches wide, according to the quantity of light desired.

Along the top I leave my burner open about one-eighth of an inch, more or less, to suit the wick intended to be used. The thinner the wick and flame the more complete the combustion of the oil will be and the greater the quantity of light will be from a given quantity of oil. Therefore I make the wick, tube, or burner as thin and as little open along the top and use as thin a wick as will draw up the oil, so as to produce an intense white light and complete combustion of the oil. I also use a great number of single wicks with success.

I make my burner on a regular bevel on each side and back and in front from the wick-wheel C down, so as to make it come round at the bottom, where the male screw is formed on it. This gives me room for the wick to fold up below the shaft of the wick-wheels and run down into the lamp. As the

shaft of the wick-wheel draws up the wick it flattens it out at the top in a perfect manner.

C is the wick wheel and shaft. I make it of brass or iron wire or any suitable metal. I cut the shaft with an engraver or suitable tool, so as to raise sharp rasp-shaped teeth on it, which take hold of the wick or wicks and move them up or down. This wick-shaft must fit close in the sides of the wick-tube to prevent the gas and smoke from getting out. I put a washer and pin on the small end of said shaft to keep it in place.

The burner or wick-tube must be as much open as to allow the wick to pass the wick-shaft freely, so as to enable the wick-wheels to move it up and not obstruct the flowing of the oil. The upper edge of said burner should be beveled off, so as to allow the air to strike the wick as low down as possible for complete combustion. When I use a number of small wicks or threads, I observe the same principle.

D is the shade-tube. I form it out of one piece of metal. The part D is cut wide and formed into a square tube, and the narrow ends are bent round and soldered to the burner or wick-tube.

E is the shade-spring. I construct it out of one piece and solder it to the shade-tube above D. On the shoulder, below E, of this spring the shade-stem rests when in its proper position for use; but for moving the lamp about and for a night-lamp the shade is let down, so as to protect the flame from the wind. For this purpose the spring E is used, and by pressing the spring to the left the shade is left down for said protection.

The flame of my lamp is easily blown out, and I find the shade very useful in order to protect it and to protect the eye from its brilliant light.

I make my shades out of tin or sheet-iron or any other metal, and paint them white inside, if necessary; and I rivet a square stem to the inside, so as to fit the shade-tube D.

The shade must be made in the shape of a screen, open at top and bottom to let the heat up.

F, Fig. 2, is a regulating-cap. I form it of one piece of metal and cut one, two, or more holes in it, as shown at Fig. 3, so as to form

one, two, or more separate jets or flames along the top of the burner to diminish the light without putting down the wick too low, as it goes out too easily when it is low down. By the use of said regulating-cap with one small hole in it my wide burner is conveniently formed into a night-lamp, which will burn but little oil, and with the shade let down over it the wind will not extinguish it.

In my experiments I have found that a three-inch burner, as shown in Fig. 1, burns no more coal-oil than the small glass-chimney lamp, and it makes as bright and steady a light.

My object in inventing said lamp is to furnish a burner to burn kerosene or carbon oil without a chimney, and I believe I have succeeded. I also believe the above lamp will burn other impure oils without a chimney.

I disclaim the wide wick as such, as it is old and well known.

What I claim as my invention, and desire to secure by Letters Patent, is—

1. The bevel lamp-wick tube B and the mode of folding up the wide wick or wicks below the wick-shaft C, substantially as described and shown.
2. The shade-tube D and its spring E, one or both to be used on my burner or not, as desired, substantially as described.
3. The regulating-cap F, to be used on my said burner or not, as desired, substantially as described and shown.

J. D. CUSTER.
